UNITED STATES PATENT OFFICE.

ROBERT S. HAYDOCK, OF CRANFORD, NEW JERSEY.

SWAGING-MACHINE.

1,324,150.

Specification of Letters Patent.

Patented Dec. 9, 1919.

Application filed February 5, 1918. Serial No. 215,458.

To all whom it may concern:

Be it known that I, ROBERT SAYRE HAYDOCK, a citizen of the United States, residing at Cranford, in the county of Union and State of New Jersey, have invented certain new and useful Improvements in Swaging Machines, of which the following is a specification.

The present invention relates to swaging machines. Swaging machines are well known, but the great difficulty heretofore has been to provide a type which will wear for a reasonable length of time and not hammer itself to pieces.

In the so-called rotary swaging machine there is a cage of rollers operating in a tool steel ring which rollers are brought to bear upon the back of hammers operating the swaging dies. From its design it is evident that the rounded surface of the rollers comes in contact on one side with the tool steel ring and on the opposite side with the back of the hammer. This results in a line contact on both sides of the rollers, which when the work is heavy, in time crushes the material and frequent replacements are necessary.

In the toggle type swaging machine the mechanism is such that all the crushing force is communicated in a series of toggle jaws through phosphor bronze pins. These pins must be made comparatively small for reasons of practicability and wear out in a short time. Similarly all the other wearing surfaces in the driving eccentric and rods and the jack shaft bearings require frequent replacements.

It is the object of this invention to provide a swaging machine in which the wear is reduced to a reasonably small amount and the period of its usefulness extended in proportion. Another object is to provide a swaging machine, simple in construction and operation, which has only a small number of elements subjected to the wear incident to the heavy work of machines of this character.

In carrying out the invention I have been guided principally by the knowledge that wear is approximately inversely proportional to the size of the wearing surface, other things being equal and in its broader aspects my invention consists in translating mechanism interposed between the power

shaft and the swaging tools or dies, so constructed and arranged that the wear is distributed over a relatively large surface, which is the principal wearing surface.

For a fuller understanding of the invention reference is had to the appended drawings in which—

Figures 1, 2 and 3 are plan view, side elevation and end view, respectively, of a swaging machine embodying the invention;

Fig. 4 a horizontal section on line 4—4, of Fig. 2;

Fig. 5 a vertical section on line 5—5;

Fig. 6 a vertical transverse section on line 6—6 of Figs. 1 and 2; and

Fig. 7 is a view in side elevation of a modification of a detail.

In the drawings in which like numerals refer to like parts 1 represents the cast iron body holding the swaging dies 2. This body 1 is preferably supported on cast-iron legs 3, 3' and 4, 4' which may be provided with holes 5 to receive the usual foundation bolts (not shown). A convenient way of securing the body 1 on the legs is by means of studs 6 extending through the yoke 7, which interconnects the legs 3 and 3' and 4 and 4', into the body 1.

The body 1 incloses a working chamber 8 terminating in an enlarged portion 9. Through this enlarged portion 9 extends a shaft 10 carrying at the outer end a cast iron fly wheel 11 which is fastened to the shaft by a forged steel key 12. The mounting for the shaft comprises a bush 13 and phosphor bronze bearing bushes 14 and 15 in the bush 13 and the body 1 respectively. This arrangement represents merely conventional means for putting the shaft 10, which has an enlargement intermediate its ends, into or out of position.

The central portion of the shaft 10 has turned upon it an eccentric part 16 which has any desired eccentricity, according to the length of the stroke, say one inch. About this eccentric part 16 is loosely fitted a bronze collar 16' which in turn is fitted within a floating collar 17 preferably of steel. The collars 16' and 17 may be held against lateral shifting by any suitable means as for instance by flanges 18 and 19 formed on the bushes 14 and 15 respectively. As the shaft 10 is revolved, the collar 17 is shifted

through a distance equal to twice the eccentricity. This movement is communicated to a machine steel plunger 20 which in turn communicates the movement to swaging dies 2.

The steel plunger is made of two parts, the front portion 20 and the rear portion 21. The front portion has preferably a plane surface 22 to contact with the collar 17 and has preferably pivotal movement relatively to the rear portion. The joint between the two plunger parts 20 and 21 may be advantageously in the form of a radius 24 as indicated in Fig. 5. The plunger part 20 is normally held in central position by means of the steel liners 25 acting as springs against the projections 26 in the part 20. As shown in Fig. 5 the walls of the body 1 have slight recesses 25' adjacent the free end of the liners. This allows the front portion 20 of the plunger to accommodate itself when the pressure is applied through the floating collar 17 and always bring about a perfect surface contact.

25 Liners 25 surround the plunger 20 and the swaging dies 2 on all sides to afford a true linear motion and take up the wear.

To force the plunger 20 toward the floating collar or ring 17 flat springs 27 and 28, located at opposite sides of the body 1, are held at one end by steel screws 29 and separated from the body by pipe spacers 30, and bear at their free ends upon pins 31 and 32 projecting from the plunger element 20.

35 The tension on the springs 27 and 28 is adjusted by tension cap screws 33 having threaded engagement in lugs 34 projecting from both sides of the body 1, lock nuts 35 being provided to lock the screws in adjusted position.

The stroke of the plunger is adjustable to any variation from 0 to the total eccentricity of the shaft. For this purpose screws or studs 36 extend into the body 1 and the bush 18 respectively and may be locked in any desired position by lock nuts 37. These screws are substantially in alignment with the pins 31 and 32 and form abutments therefor. The openings 38 and 39, through which the pins 31 and 32 project, are made of such diameter as to allow for the reciprocating movement of the pins toward and away from the collar 17.

55 Intermediate the last swaging die and the adjacent wall of the body 1 is inserted a wedge 40, as is customary, to compensate for the wear. This wedge is held in adjusted position by locking plate 41 adjustably secured to the body by a screw 42 and jam nuts 42'. To facilitate changing the dies, the machine is provided with a cast iron door 43 which also has a steel liner plate 25''. This door is hinged by means of a hinge pin 46 to the hinge block 44 which in turn is detachably connected to

the body 1 by bolts 45. The door 43 may be locked by a suitable latch mechanism operated by a handle 43' (Figs. 2 and 3).

The machine may be driven from a line shaft or an electric motor 47 may be mounted directly upon it, as shown. This electric motor is shown as driving a pulley 48, from which the fly wheel 11 is driven by a belt 49 running over an idler 52 for taking up the slack. The shaft 55 of the idler 52 is mounted in a bearing 53 bolted to the body 1 by bolts 54.

50 The steel liners 25 are removably attached to the body 1 by means of screws 50 or in any other suitable manner.

The machine is provided with the necessary oil passages, one being indicated at 51 leading into the enlarged portion 9 of the working chamber 8. This enlarged portion forms an oil well providing for the efficient 85 lubrication of the floating collar and its bearing.

55 The operation is as follows:

The tension of the springs 27 and 28 is 90 adjusted to any desired degree. The screws 36 are then adjusted to fix the stroke of the plunger and to hold the sliding plug 20 out of contact with the steel floating ring 17 for the larger portion of the revolution of the shaft 10. During this period the floating 95 ring revolves with the shaft, but when the eccentricity of the shaft is sufficient to bring the floating ring 17 in contact with the plunger 20, the friction between these two pieces causes the ring 17 to cease revolving with 100 the shaft. This condition continues during the stroke. At the end of the stroke the floating ring 17 again leaves the plunger plug and rotates again with the shaft. This 105 action of alternately revolving about the shaft and rotating with it causes the floating ring to always present a new surface to the plunger plug. By this continuous creeping movement of the floating ring the wear is uniformly distributed over the whole surface thereof.

110 The combined cam and hammer stroke thus obtained is particularly effective for the purpose indicated.

In order to swage a tube, rod or the like, 115 the operator inserts the end of the particular article into the appropriate die and pushes it forward at the end of each swaging stroke.

120 While I prefer to make the surface 22 of the plunger plug 20 plane, it may be more or less curved.

The plunger, which is shown in Fig. 5 as composed of two parts fitted together on a half-circle, may be advantageously 125 made as shown in Fig. 7. The body of the plunger may be made of the desired length, then bored to provide cylindrical surfaces 60 and 61, whereupon the body may be cut in two parts 20' and 21'. A shaft 62 may 130

then be interposed between the two parts 20' and 21' to fit the surfaces 60 and 61. This shaft may be provided with a bore to receive a pin 63 similar to pins 31 and 5 32 in Fig. 4.

In this way the two component parts of the plunger 20' and 21' are interconnected by a radius joint in a mechanically simple manner.

10 I claim:—

1. In a machine for working metal, the combination with a tool, of a plunger mounted for sliding movement toward and away from the tool, a rotatable shaft having an eccentric portion, a collar loosely mounted upon the eccentric and a ring loosely mounted upon the said collar, said elements being so constructed and arranged that a blow is delivered to the plunger during a revolution of the shaft.

2. In a swaging machine the combination with swaging dies, of a rotatable shaft having an eccentric portion, a ring having a loose fit upon the eccentric portion, a plunger mounted for sliding movement toward and away from the dies in the plane of movement of said ring, means for forcing the plunger toward said ring and means for limiting the movement of the plunger toward the ring.

3. In a swaging machine the combination with swaging dies, of a rotatable shaft having an eccentric portion, a ring having a loose fit upon the eccentric portion, a plunger mounted for sliding movement toward and away from the dies in the plane of movement of said ring, means for forcing the plunger toward said ring and means for adjustably limiting the movement of the plunger toward the ring.

4. In a swaging machine the combination with swaging dies, of a rotatable shaft having an eccentric portion, a collar loosely mounted thereon, a ring loosely mounted on 45 the collar, a plunger having sliding movement toward and away from the dies in the plane of movement of the said collar and ring and means for forcing the plunger toward the said ring.

5. In a swaging machine the combination with swaging dies, of a rotatable steel shaft having an eccentric portion, a bronze collar loosely mounted thereon, a steel ring mounted on the collar, a plunger having 55 sliding movement toward and away from the dies in the plane of movement of the said collar and ring and means for forcing the plunger toward the said ring.

6. In a swaging machine, the combination with swaging dies, of a rotatable shaft having an eccentric portion, a ring having a loose fit on the said eccentric portion, a plunger mounted for sliding movement toward and away from the dies and means 65 for forcing the plunger toward the said ring,

said plunger consisting of two elements interconnected by a radius joint.

7. In a swaging machine, the combination with swaging dies, of a rotatable shaft having an eccentric portion, a ring having a loose fit on the said eccentric portion, a plunger mounted for sliding movement toward and away from the dies, said plunger consisting of two elements interconnected by a radius joint, one of said elements being adapted to contact with the outer face of the ring, means for forcing the said plunger toward the said ring and means for adjustably limiting the movement of the plunger toward the ring.

8. In a swaging machine, the combination with swaging dies, of a rotatable shaft having an eccentric portion, a ring having a loose fit on the said eccentric portion, a plunger mounted for sliding movement toward and away from the dies, said plunger consisting of two elements interconnected by a radius joint, one of said elements being adapted to make contact with the outer face of the ring, spring means for forcing the said plunger toward the said ring, means for adjusting the tension of the spring means and means for adjustably limiting the movement of the plunger toward the ring.

9. In a swaging machine, the combination with swaging dies, of a rotatable shaft having an eccentric portion, a ring having a loose fit on the said eccentric portion, a plunger mounted for sliding movement toward and away from the dies, said plunger consisting of two elements interconnected by a radius joint, one of said elements being adapted to make contact with the outer face of the ring, pins extending laterally from one of the plunger elements, leaf springs bearing on the said pins, a support for the springs and means for adjusting the tension of the springs.

10. In a swaging machine, the combination with swaging dies, of a rotatable shaft having an eccentric portion, a ring having a loose fit on the said eccentric portion, a plunger mounted for sliding movement toward and away from the dies, said plunger consisting of two elements interconnected by a radius joint, one of said elements being adapted to make contact with the outer face of the ring, pins extending laterally from one of the plunger elements, leaf springs bearing on the said pins and tending to force the plunger toward the ring, a support for the springs, means for adjusting the tension of the springs and adjustable stops between the ring and the pins to intercept the path of the pins.

11. The combination of a shaft having an eccentric portion, a floating ring on the eccentric portion, a plunger element, positioned to contact with the plunger, a slide

way for said plunger element having resilient walls in the plane of the floating ring.

12. The combination of a shaft having an eccentric portion, a floating ring on the eccentric portion, a slide way substantially in the plane of the floating ring and a plunger in the slide way adapted to have motion toward and away from the floating ring, steel liners between the plunger and the walls of the slide way and a clearance between the said liners and the walls of the slide way at the end of the slide way adjacent the ring.

13. The combination of a slide way having resilient side walls at one end and a plunger having sliding motion in the slide way, the plunger being composed of two parts, and a radius joint between the abut-

ting ends of the said parts to admit of a relative pivotal motion in the plane of the resilient walls.

14. In a swaging machine the combination with swaging dies, of a rotatable steel shaft having an eccentric portion, a bronze ring having a loose fit on the said eccentric portion, a steel ring having a loose fit on the bronze collar, a plunger mounted for sliding movement intermediate the ring and the dies, means for urging the plunger toward the ring to project within the sphere of action thereof and means for adjustably limiting the movement of the plunger toward the ring.

In testimony whereof I affix my signature.

ROBERT S. HAYDOCK.
